EDWIN NORTON, OF NEW YORK, N. Y.

SHEET-METAL BOX.

1,079,433.

Specification of Letters Patent. Patented Nov. 25, 1913.

Application filed March 6, 1906. Serial No. 304,508.

To all whom it may concern:

Be it known that I, EDWIN NORTON, citizen of the United States, residing at borough of Manhattan, in the county of New York and State of New York, have invented new and useful Improvements in Sheet-Metal Boxes, of which the following is a specification.

My invention relates to sheet metal boxes, 10 used for packing sardines and other articles. The bodies of such boxes are commonly stamped up in a single piece, of tin plate, or other sheet metal coated with a noncorrosive substance, and the one piece covers are attached, after the box is filled, by double 15 seaming without the use of solder.

My invention consists in a new construction by which an improved box, with certain great advantages is produced; for instance, a much stronger seam is obtained insuring a tight closure to prevent leakage, access of air to the contents, etc.; the box bodies may be nested occupying the smallest space, so that they may be made at the most 25 convenient place of manufacture and transported to the place of use, without excessive freight charges, etc.; the packed and closed boxes may be opened conveniently by the purchaser without the use of a can opener, 30 key or other special tool.

The important features of my invention are to construct the boxes with slightly flaring sides and to provide the usual horizontal flange at the top of the box with a 35 downturned continuation or supplementary flange, which, in nesting the bodies for storage, transportation, etc., rests on the horizontal flange of the box below, permitting the nesting of the bodies in convenient large 40 numbers, and yet preventing the wedging of the bodies together, which made it difficult to separate them.

When the covers are applied and the boxes closed, the cover flange is bent around 45 the supplementary flange and they are turned together against the body, producing a strong, tight and rigid seam, which not only insures against leakage but braces and strengthens the entire box,—a point of great 50 importance in boxes which are made of the lightest possible sheet metal and packed in large quantities to be transported long distances, by various kinds of carriage and under trying circumstances. Heretofore to 55 reinforce such boxes they have commonly been provided with a bead at the lower

margin. To provide a simple means for opening these boxes, I form them with a bead not at the margin but slightly within it and with a narrow shoulder, and score the 60 bottom of the body between the bead and the side, which does not weaken the box for its main purpose. The box may then easily be opened by striking on the bead, whereby the bottom is separated along the score. 65

My invention is shown applied to a desirable form of box body in the drawings here-with, in which the reference numerals of the specification indicate the corresponding parts in all the figures.

Figure 1 is a cross section showing nested bodies. Fig. 2 is a bottom plan of a body. Figs. 3, 4 and 5 are enlarged, partial sections showing the various steps and position of the flanges in the process of applying 75 and securing the cover. Fig. 6 shows a slight modification in the form of the seam. Fig. 7 is an enlarged, partial section of the bottom showing the position of the score. Fig. 8 shows a flange of the prior art to 80 illustrate the importance of my invention.

In the figures, 1 indicates the box body struck up of one piece with flaring sides 2 and the marginal flange 3 provided with the extra flange 4 downturned therefrom at a 85 right angle, or more or less. 5 is the bead on the bottom 6, set in from the corner 7, to leave a small shoulder 8. All this is effected at one operation. $3\frac{1}{2}$ °, more or less, is a desirable angle for the tapering sides; about 90 one-eighth inch a desirable width for the top flange, and about one-sixteenth inch a desirable depth for the extra flange. A score 9 is made in the bottom between the bead and the side. This is preferably continuous in the inner surface of the bottom, but may be made in the exterior, or in some cases, as where heavier sheet metal is used, opposite scores may be made in both surfaces. The side of the bead next the score 95 may be made somewhat straighter than the other side.

12 indicates the cover, having the horizontal flange 13 wider than the combined width of the two body flanges. When the 105 cover is set in place, its flange is bent over and around the body flanges by any suitable machine, and the supplementary flange is rolled into the joint or seam, acting as a packing strip to increase the strength 110 and tightness. The operations of closing are indicated in Figs. 3, 4 and 5. By com-

paring the finished seam of Fig. 5, with the old seam shown in Fig. 8, it will be understood that my construction not only strengthens the seam but insures against leakage. The angle between the horizontal flange and the supplementary flange may be slightly round, favoring the operation of the seaming rollers.

In Fig. 6 is shown a slight modification 10 in the form of the finished seam in which the cover flange merely overlaps the supplementary body flange; but I prefer the seam of Figs. 4 and 5, in which the body flange is rolled around the supplementary flange 15 to give an additional lock, and forming a seam of five thicknesses.

By reference particularly to Figs. 2 and 6, it will be seen how the box may be opened to any desired extent by inverting the box 20 and striking sharp blows along the bead, for instance with a stone. The tapering side will act as an abutment or resistance to the blows, and the bottom will be sheared along the score, and will clear the side, if 25 forced in more or less.

While I have shown a sardine box commonly made rectangular with rounded corners, yet it will be understood that I do not limit myself to applying my invention to 30 any particular form of box or vessel, or to the exact form and arrangement of the parts, or to use without solder. For instance, if the object should be merely the prevention of wedging in nested boxes, a 35 different form of downturned projection might be substituted for the supplementary flange. I am aware that tin pans have been nested, but the objection to the wedging (with the difficulty of separation and with 40 injury to the boxes), in connection with

boxes of the kind here particularly referred to has proved so great that the boxes have heretofore been made with straight sides preventing nesting, and it was necessary to manufacture the boxes, often uneconomically, near the place of use. 45

Having thus described my invention, what I claim as new and desire to secure my Letters Patent, is:—

1. As a new article of manufacture, a 50 sheet metal box having the bottom thereof formed with an outwardly extending bead projecting beyond the plane of the bottom, and located slightly inwardly from the side of the bottom of the box, and a continuous 55 score on the inner face of the bottom between said bead and the side of the box.

2. As a new article of manufacture, a sheet metal box formed of a single piece of metal and having an outwardly extending 60 bead formed in its bottom, said bead projecting beyond the plane of the bottom, and being located slightly inwardly of the side wall of the box, the side wall of the bead adjacent the side wall of the box being at 65 substantially right angles to the bottom of the box, whereby said wall of the bead and the side wall of the box extend in substantially the same general direction, said bottom being formed with a score adjacent said bead and between it and the side wall of the box. 70

In testimony whereof I have signed my name to this specification in the presence of two subscribing witnesses.

EDWIN NORTON.
